UNITED STATES PATENT OFFICE.

ODILON BRISBOIS, OF CHICAGO, ILLINOIS, ASSIGNOR OF ONE-HALF TO WILLIAM LORIMER, JR., OF CHICAGO, ILLINOIS.

TELEPHONE SYSTEM.

1,123,476.

Specification of Letters Patent.

Patented Jan. 5, 1915.

Application filed January 7, 1913. Serial No. 720,805.

To all whom it may concern:

Be it known that I, Odilon Brisbois, a citizen of the United States, residing at Chicago, in the county of Cook and State of Illinois, have invented certain new and useful Improvements in Telephone Systems, of which the following is a specification.

This invention relates to a telephone system of that general class in which a prepay or coin box is used, and to the instruments used in conjunction with such system.

The invention has particular reference to party line telephone systems of the automatic type as distinguished from the Bell or manual type. In the automatic system the central exchange is provided with a number of selector mechanisms which are operated by impulses of current received from the calling stations and which serve to effect connection between the calling and called stations. The impulses of current for operating these selector's are delivered to the lines by suitable signaling mechanisms which are usually mounted in the bases of the telephone instruments themselves. These signaling mechanisms deliver the aforesaid impulses or pulsations of current to the lines for the purpose of actuating the selector mechanisms in the exchange.

At the outset, it will be understood that where, in the specification and claims, I speak of a "party line," I have reference to an electric circuit extending from a central exchange, and to which circuit are connected a number of separate telephone instruments or stations, any one of which is adapted to use the line either as a calling or called station. It will also be understood that where I speak of a "station" I have reference to a telephone instrument for receiving or transmitting messages taken in conjunction with the associated and immediately adjacent accompanying mechanisms and connections. Thus, under ordinary circumstances, a "station" would include the telephone instrument itself, the ringing box, the coin box, and the immediately adjacent and interrelated connections.

A serious objection has been raised to the use of automatic telephones for party line service in which use is made of prepay stations, for the reason that heretofore, as far as I am aware, there has not been such an interdependence between the operation of

the signaling and selecting mechanism, 55 the listening and talking mechanism, and the coin box mechanism, as to make it imperative that a calling party should place a coin in his coin box before he could secure connection with a called party. 60

One of the main objects of the present invention is to so interrelate and connect the above named mechanisms, that it will be impossible for a calling party to effectively operate the signaling mechanism of his station 65 for the purpose of actuating the selector mechanism in the exchange to secure connection with a called party, until a coin has been dropped into his coin box and stands on the float arm thereof in the neutral position. In this way the calling party will be forced to insert or drop his coin into his coin box before it will be possible for him to take any effective steps toward securing connection with the called party. 75

Another object of the present invention is to so interrelate and interconnect the different instruments and mechanisms of each station as to make it necessary to throw the coin from the float arm before a conversation can be carried on with a called party who may have responded. Nevertheless, this result is accomplished without destroying or injuring the capability of the calling station to operate as a receiving station, thus 85 making it possible for the calling party to tell, by listening in his receiver, whether or not the called party has responded, or whether the called line is busy, thus enabling the calling party to know whether to 90 "collect" his coin into the coin box, or to "return" the same.

Both of the above named objects are directed toward the feature of making it necessary for a calling party to place his coin 95 in his coin box in order to effectively operate his signaling mechanism for the purpose of securing connection with a called party.

Another feature of my invention has reference to the interrelationship existing between the different parties and stations of an automatic party line telephone system. The automatic telephone, as previously used in party line service, as far as I am aware, has always been subject to the objection that, in 100 case one party of such party line obtains connection with another station, and then another party of such party line cuts in onto

the line by raising his receiver, he thereby automatically cuts off the connection of the first party with the party line, or at least impairs that connection to such an extent 5 that it then becomes necessary for such first party to insert another coin into his coin box in order to again gain access to the line or connection with the party to whom he was talking. This objection is of such a 10 serious nature that, up to the present time, the automatic telephone has been excluded from the field of prepay party line service, as far as being a practical instrument is concerned.

15 Another objection to the use of the automatic telephone in connection with prepay mechanisms, as far as I am aware, is that the inherent nature of such instrument as now constructed is such that the insertion 20 of a coin into the coin box does not always accomplish the intended result of placing the calling party in communication with a called party. Whenever the mechanism fails to operate properly, the insertion of 25 another coin becomes necessary, and this is, of course, a serious objection to the use of such an instrument.

Both of the objections enumerated immediately above are due to the inherent nature 30 of the prepay mechanism which is now used for automatic telephone service, and also to the manner of interconnecting such prepay mechanisms with the automatic telephone instruments. One of the features of such interconnection and interrelationship is that the listening and talking circuit is not cut directly onto the line by the raising of the telephone receiver, but depends for its continuity upon the effectiveness of an electrical 35 contact in the prepay mechanism. If for any reason this contact fails to operate properly the transmitting and receiving mechanism will be ineffective for the purposes intended. It sometimes happens that the insertion 40 of a coin into the form of coin box at present in use fails to cause this contact to be properly established within the coin box, with the consequence that another coin must be inserted as was previously stated.

50 One of the objects of the present invention is to overcome the aforementioned difficulties by the provision of an arrangement such that the act of raising the receiver from the hook will serve to bridge the transmitter 55 and receiver of the calling instrument directly across the line without the necessity of closing or actuating any contacts in the coin box mechanism itself.

60 Other objects and uses of systems and instruments embodying features of the present invention will appear from a detailed description of the same which consists in the features of construction and the arrangement of parts and circuits shown and described in the specification and claims.

In the drawings: Figure 1 shows an electrical diagram of one arrangement of parts and connections embodying features of my invention; Fig. 2 shows a bottom view of certain contacts of the signaling mechanism 70 in the base of the instrument; Fig. 3 shows a cross section through a coin box embodying the features of that shown in Fig. 1, Fig. 3 being taken on line 3-3 of Fig. 4 looking in the direction of the arrows; Fig. 4 shows a section taken on line 4-4 of Fig. 3 looking in the direction of the arrows; Fig. 5 shows a section taken on line 5-5 of Fig. 4 looking in the direction of the arrows; Fig. 6 shows in enlarged detail the 80 float arm and contact leaves of the coin box shown in Figs. 3 and 4, the contact leaves standing in their normal position; Fig. 7 shows a view similar to Fig. 6, the contact leaves being forced down by the weight of a coin resting on the float arm while the same stands in the neutral position; Fig. 8 shows in detail a portion of the interior of the coin box of Figs. 3 and 4, showing one of the contact leaves whereby a momentary 90 contact is effected by the passage of a coin along the coin chute; Fig. 9 shows a bottom view of the base of a telephone instrument provided with certain of the contacts shown in the diagram of Fig. 1; Fig. 10 shows a detail section taken on line 10-10 of Fig. 9 looking in the direction of the arrows; Fig. 11 shows a detail section taken on line 11-11 of Fig. 9 looking in the direction of the arrows; Fig. 12 shows a vertical section 100 on small scale showing the mechanical connection between the receiver hook and certain of the contacts in the base of the telephone instrument; Fig. 13 shows a wiring diagram showing a modified system of connections embodying certain features of my invention; Fig. 14 shows a detail view of the bottom of a telephone instrument similar to that shown in Fig. 9, but provided instead with certain of the contacts shown in 105 the diagram of Fig. 13; Fig. 15 shows a section taken on line 15-15 of Fig. 14 looking in the direction of the arrows; Fig. 16 shows an enlarged detail of the float arm of the coin box used in the arrangement shown 110 in the diagram of Fig. 12 with the contact leaves standing in normal position; and Fig. 17 shows a view similar to that of Fig. 16, but with the contact leaves in the position which they occupy when a coin is resting in 115 neutral position on the float arm.

Before considering in detail the mechanical devices which I have illustrated for carrying into effect certain of the features of my invention, I will first describe the corresponding electrical diagrams so as to facilitate an understanding of the interrelationship which exists between the different mechanical parts illustrated in the several drawings.

Fig. 1 shows the electrical connections of one arrangement embodying features of my invention. In this case the two wires 20 and 21 are the wires of a party line leading from an exchange 22. I will describe in detail only the connections of one of the stations connected to the party line, for the reason that the connections in each of the other stations on said party line will be the same or similar to those illustrated. The lines running into the several stations are designated 23, 24, 25, and 26. The two wires of the line 26 are the wires 27 and 28, these being the wires leading to the particular station under consideration.

The call or ringing box is designated 29. It is provided with the usual ringing coils 30 and 31 and with the resistance 32, should that be desired. The incoming and outgoing line wires 27 and 28 connect to the terminals 33 and 34 respectively. The ringing coils are connected in series between the outgoing terminal 34 and a ringing terminal 35 in the usual manner.

The base of the telephone instrument is designated by the numeral 36, the transmitter by the numeral 37, and the receiver by the numeral 38. The operation of the receiver hook serves to raise and lower a post 39, said post being raised or pulled away from the observer in Fig. 1 when the receiver is placed on the hook and being lowered or forced toward the observer in Fig. 1 when the receiver is raised from the hook. These operations serve to raise and lower a leaf contact 40, so that when the receiver is placed on the hook to raise the post 39, said leaf contact will follow the post until it strikes a stationary contact point 41. On the other hand, when the receiver is raised from the hook, so that the post is forced down, the leaf contact will be pressed into engagement with another leaf contact 42, at the same time breaking the contact which had previously existed between the leaf 40 and the point 41.

The contact points 43, 44, 45, and 46 are the contact points of a signal mechanism, such as is ordinarily used on an automatic telephone. Under normal conditions, the points 43 and 44 remain in contact, but each time the selector mechanism is operated the points 45 and 46 are brought into contact, and are held in contact while the points 43 and 44 are separated and brought together a number of times corresponding to the number of electrical impulses which it is desired to impress upon the selector mechanism in the exchange. The operation of this signaling mechanism is well known in the art and I will not describe the same in further detail.

The post 39 carries a contact point 47 which travels up and down with it, wiping against a leaf contact 48 in the middle por-

tion of each up or down movement to thereby establish a momentary contact therewith during each up or down movement.

The incoming wire 27 is carried by means of a lead 49 from the post 33 to a post 50 in the base of the instrument, and the outgoing wire 28 is connected by a lead 51 from a post 52 in the base of the instrument to the post 34. The ringing post 35 is connected by a lead 53 to a post 54 in the base 75 of the instrument. The posts 50 and 52 are generally designated the "line posts," and they are the posts whereby communication is established between the telephone and the line during ordinary service. A lead 55 connects the post 50 to the leaf contact 40, and a lead 56 connects the stationary contact point 41 with the ringing post 54. From the above it will be seen that, as long as the receiver remains on the hook, a connection 85 is established between the posts 50 and 54 thereby placing the ringing box directly across the lines 27 and 28. When thus connected, the ringing box is ready to receive any ringing currents which may be delivered over the lines from the exchange.

The transmitter is connected by the leads 57 and 58 with a pair of "transmitter posts" 59 and 60 in the base of the instrument, and the receiver is connected by a pair 95 of leads 61 and 62 with a pair of "receiver posts" 63 and 64 in the base of the instrument. A permanent connection 65 is placed between the posts 60 and 63, so that said posts always are in electrical communication.

It is desired to place the transmitter and receiver in series on the line—that is, to "bridge" them across the line—whenever it is desired to carry on a conversation. A 105 lead 66 connects the leaf contact 42 with the post 64, thereby establishing direct communication with one side of the receiver. Thence the circuit extends through the connection 65 to the transmitter, thus placing 110 the receiver and transmitter in series. A lead 67 connects the post 59 to the contact points 43 and 45 of the signaling mechanism through the medium of leads 68, 69, and 70, and a lead 71 places the contact 115 point 44 in communication with the post 52, so that as long as the points 43 and 45 remain in contact, communication is established between the transmitter post 59 and the outgoing line post 52.

From the above it will be seen that, as soon as the telephone receiver is raised from the hook, the ringing circuit is broken, by reason of the forcing of the leaf contact 40 away from the contact point 41, but that immediately the transmitter and receiver are bridged across the line by the closing of contact between the leaves 40 and 42. Under these circumstances, a conversation may be carried on in the usual manner. I also wish 120

to point out the fact that, under these circumstances, the continuity of the listening and talking circuit is entirely independent of the engagement of any contacts in the 5 coin box presently to be described, and that therefore the effectiveness of the talking and listening circuit is not dependent on the effectiveness of any contacts in the coin box.

10 When it is desired to signal the exchange so as to operate the selector mechanism therein, the contacts 45 and 46 are to be brought together and held together while the contacts 43 and 44 are separated and 15 brought together the desired number of times to give the desired number of impulses of current on the line for operating the selector mechanism. This signaling current should be sent to the exchange directly 20 without the necessity of passing through the transmitter and receiver of the station. Therefore, I connect a lead 72 from the receiver post 64 to the contact point 46, so that said contact point will be brought to 25 potential equal to that of the incoming line 27 the instant the telephone receiver is raised from the hook. Assuming that the receiver has been raised so as to energize the contact point 46 the signaling mechanism 30 may be operated. This will bring the points 45 and 46 together, and each time the points 43 and 44 come together an impulse of current will be delivered to the line. Such impulses will be delivered over the 35 circuit 33, 49, 50, 55, 40, 42, 66, 64, 72, 46, 45, 70, 69, 43, 44, 71, 52, 51, and 34.

From an examination of the above, it will be seen that, unless other means are provided for breaking the signaling circuit 40 or for preventing its proper functioning, the selector mechanism at the exchange could be operated by operation of the signaling mechanism without the necessity of inserting a coin into the coin box of the calling station. I have, however, provided means for guarding against the above contingency, whereby the signaling mechanism cannot properly function until a coin has been dropped into the box. This is an interlocking means and is based upon the principle that the selector mechanism of the exchange will only operate through the medium of pulsations of current properly delivered from the calling station. Any 55 means or mechanism whatsoever which will prevent the delivering of such pulsations of current will effect the result which I desire, and one of the features of my invention consists in providing suitable mechanisms 60 and connections for preventing the delivery of such pulsations of current from the signaling mechanism of the calling station until a coin has been properly inserted into the coin box.

65 In the particular arrangement illustrated

in Fig. 1, I have provided suitable connections whereby the points 43 and 44 of the signaling mechanism are permanently bridged or shunted until a coin is inserted into the box. For this purpose, I have provided within the coin box suitable contacts which remain together until a coin rests on the projecting end of the float arm of the coin box, a movable contact being carried thereby, which contact will be broken by the 70 weight of the coin resting upon it. The float arm proper is designated by the numeral 73. It is pivoted at the end 74 in the usual manner, so that it can swing either toward or from the observer, as in Fig. 1, 80 but it normally stands in a neutral position where it will sustain the coin either directly or through the medium of another contact. This float arm carries a pair of upper contact leaves 75 and 76 and a pair of lower 85 contact leaves 77 and 78. An insulating block 79 joins the leaves 76 and 77 mechanically together, although they are electrically insulated from each other. The leaf 76 also carries a contact pin 80, which pin, however, is insulated from the said leaf and from the float arm proper 73 by an insulating block 81, but which pin is electrically connected to the leaf 77. The swinging end 82 of the leaf 76 projects into the path of 90 the coin as the same descends down the coin chute, so that the coin will strike and rest upon said projecting end as long as the arm stands in the neutral position. From the above it will be seen that the springs 76 and 100 77 normally stand in the position illustrated in Fig. 1, so that under such circumstances the leaves 75 and 77 are in electrical contact through the medium of the pin 80, while the end 82 is out of contact from the float 10 arm 73 and the leaves 77 and 78 are also out of contact from each other.

It will be understood that the coin box is designated by the numeral 83. It is provided with the terminal posts 84, 85, 86, 87, 11 and 88. The leaf contact 75 is connected to the terminal post 86 through the medium of the leads 89 and 90, while the leaf contact 77 is connected to the terminal post 87 through the medium of the lead 1. The 11 terminal post 86 connects to the outgoing line post 52 on the base of the instrument through the medium of the lead 92, while the terminal post 87 connects to the transmitter post 59 on the base of the instrument through the medium of the lead 93. It will be seen that the posts 59 and 52 are directly connected to the contacts 43 and 44 of the signaling mechanism, so that as long as said posts remain electrically connected together, any opening and closing or making and breaking of the contacts 43 and 44 will be ineffectual to open and close the signaling circuit as far as the production of pulsations of current is concerned. 12

This connection between the posts 59 and 52 is established through the medium of the leads 92 and 93 and the leaf contact 75 and the pin 80 carried by the float arm of the coin box. Therefore, until this shunting circuit is broken, it will be ineffectual to make and break the contacts 43 and 44. As soon as a coin is dropped into the coin box and rests on the projecting end 82 of the leaf contact 76, the same will be forced down to carry the pin 80 away from the leaf contact 75, thereby opening this shunting circuit and permitting the signaling mechanism to function properly for the production of the pulsations of current necessary to operate the selector mechanism in the exchange.

It will presently be seen that the act of hanging up the receiver serves to throw an impulse of current into the coin box in such a manner as to swing the float arm in the direction necessary to return the coin. Therefore, unless means are provided for preventing the calling party from carrying on a conversation while the coin stands on the float arm, it will be seen that the telephone company might be deprived of their fee for the service. I have, therefore, provided interlocking connections whereby, as long as the coin stands on the float arm in the manner above described, the talking circuit, by which is meant the circuit including the transmitter and receiver, is so interrupted or interfered with that a conversation could not be carried on between the calling station and any other station to which connection might be made. In the particular arrangement illustrated and described herein, this interruption is effected by shunting the transmitter with a circuit of such resistance as to prevent the proper delivery of talking currents to the line when the transmitter is spoken into. It will presently appear, however, that any other suitable means might be substituted for accomplishing this result or for interrupting the talking and listening circuit for this or for a similar purpose.

It has been shown that, as long as the coin rests on the float arm, it depresses the projecting end of the leaf contact 76 and also the leaf contact 77 through the medium of the insulating pin 79. This depression of the leaf contact 77 establishes an electrical connection between the leaves 77 and 78. It was previously stated that the contact 77 connects by means of the lead 91, terminal 87, and lead 93, with the transmitter post 59 in the base of the instrument. The leaf contact 78 connects by means of the leads 94 and 95 to the post 88, and the post 88 connects by the means of the lead 96 with the transmitter post 60 in the base of the instrument. Therefore, as soon as the leaf contacts 77 and 78 are brought together by

the presence of a coin standing on the projecting end 82 of the leaf contact 76 a direct connection will be established between the transmitter posts 59 and 60, thereby shunting the transmitter and interfering with its operation in the manner previously described. However, it will be seen that as long as the above condition exists, the receiver will be connected directly across the lines through the medium of the circuit 33, 75 49, 50, 55, 40, 42, 66, 64, 62, receiver 38, 61, 63, 65, 60, 96, 88, 95, 94, 78, 77, 91, 87, 93, 59, 67, 68, 69, 43, 44, 71, 52, 51, and 34. In view of the fact that, under these circumstances, the current through the receiver 80 would be practically double its normal amount there might be danger of burning out the receiver. To obviate this possibility, I have provided a resistance 97 between the leads 94 and 95 which resistance is suitably 85 proportioned to allow that amount of current to be shunted away from the transmitter as to effectually prevent the carrying on of a conversation, but without the danger of producing an excess current through 90 the receiver which might damage or permanently injure the same.

A study of the above mechanisms and connections will show that, in the particular arrangement illustrated in Fig. 1, the operation of the listening circuit, that is, of the receiver, is not interfered with by the presence of a coin standing on the projecting end 82 of the spring contact 76, but that the presence of such coin simply interrupts or 100 interferes with the talking or transmitting circuit. Therefore, it is possible with the above arrangement for the calling party to listen in his receiver until he hears a response from the called station, whether such response be the voice of the called party, or a signal from the exchange showing that the line of the called party is busy. In either circumstance, the calling party can 105 adjust himself to the particular circumstances and act accordingly. If the called party properly responds, the calling party can carry on a conversation with him by first collecting the coin which has been standing on the projecting end 82 of the 110 leaf contact 76 so as to permit the leaf contacts 77 and 78 to separate. This collection is effected by means of a push button 98 which may be placed at any suitable point 115 for operation by the calling party, and in 120 the particular arrangement illustrated is placed on the side of the coin box.

The coin box is provided with two relays for throwing the float arm in the one direction or the other depending upon the circumstances: when thrown in one direction the float arm serves to release the coin into the collecting box, and when thrown in the other direction it serves to deliver the coin 125 back to the calling party. These coils are 130

the coils 99 and 100 of Fig. 1, and for purposes of convenience we shall designate the coil 99 the "collect coil" and the coil 100 the "return coil." A lead 101 extends from the 5 incoming post 50 in the base of the instrument to the terminal post 85 on the coin box. From this point leads 102 and 103 connect to the float arm 73 so that the same is constantly energized with current of the 10 polarity of the post 50 in the base of the instrument, which polarity is that of the wire 27. The leaf contact 76 connects by a lead 104 to one side of the push button 98, the other side of the push button connecting 15 by a lead 105 to one end of the collect coil 99. The other end of said collect coil connects by a lead 106 with the lead 90 which in turn connects to the terminal post 86 of the coin box.

20 From the above it will be evident that depression of the button 98 will close a circuit through the collect coil 99 as follows: 33, 49, 50, 101, 85, 102, 103, 73, 76, 104, 98, 105, through the collect coil 99, 106, 90, 86, 92, 25 52, 51, and 34. Therefore, as soon as the calling party has obtained the desired connection, he may depress the button 98, thereby energizing the collect coil in the direction from the lead 105 to the lead 106, thus causing 30 the float arm to be swung in the proper direction for collecting, and thereby clearing the float arm, collecting the coin, and separating the leaf contacts 77 and 78 to remove the shunt connection from the transmitter. This last operation will serve to 35 remove the impediment which previously existed to the proper functioning of the transmitter, thus permitting a conversation to be carried on freely with the other station. It will also be seen that the connection is thus reestablished between the pin 80 and the leaf contact 75, thereby again restoring the impediment to the proper functioning of the selector mechanism, so that 40 45 another coin will have to be inserted into the coin box before the selector mechanism can be operated to obtain a similar connection with another party.

It was previously stated that, in case of 50 failure to secure the desired connection with the called party, the return of the coin was effected by a replacement of the receiver on the telephone hook. This is accomplished by energizing the return coil 100, by a 55 momentary impulse of current created by the momentary contact which is established between the points 47 and 48 in the base of the instrument as the receiver is placed on the hook. The stationary contact 48 connects to a terminal post 107 on the base of the instrument, which post in turn connects by a lead 108 to the terminal post 84 of the coin box. The latter connects by a lead 109 to one end of the return coil, the other end 60 65 thereof connecting by the lead 110 to the

lead 102. Under these circumstances, when a momentary contact is established between the points 47 and 48 as above described, an impulse of current is delivered through the coil by the circuit 33, 49, 50, 101, 85, 102, 70 110, return coil 100, 109, 84, 108, 107, 48, 47, 111, 71, 52, 51, and 34. Therefore the act of replacing the receiver on the telephone hook will return the coin in case the same has not previously been collected. 75

It was previously stated that one of the objects of the present invention is to provide an arrangement whereby, in case the party line to which the calling station is connected happens to be in use, it will be impossible 80 to interfere with the operation thereof, and that in case a coin should be inserted into the coin box of such interfering station, such coin would be automatically and immediately returned. This result I am 85 enabled to accomplish by reason of the fact that the automatic telephone system, as ordinarily used, is such that, when a line is in service, its polarity is automatically reversed by the selector mechanism in the exchange and remains reversed as long as such line is in use. I make use of this fact for the purpose of delivering a momentary impulse of current through the relay coils of 90 the coin box in a reverse direction by the insertion of a coin into the slot of such coin box, thereby swinging or throwing the float arm to the position which it must occupy in order to return the coin. Although this 95 impulse is momentary in character, being delivered by passage of the coin along the coin slot, still I will presently describe one form of mechanism which I have provided for locking the float arm in the return position, so that a single impulse of current 100 which throws the float arm to return position will be sufficient to lock said arm in such position, thereby forcing the coin to pass down to the point of exit even though 105 the momentary impulse of current has 110 ceased.

In the particular arrangement illustrated contacts 112 and 113 are placed in or adjacent to the coin chute so that said contacts will be electrically brought together by the 115 passage of the coin along the chute. The contact 112 connects to one end of the return coil through the lead 114, while the contact 113 connects to the other end of the collect coil through the medium of the lead 120 115. When the coin passes along the chute to bring the contacts 112 and 113 together, a momentary impulse of current will be delivered over the following circuit in the direction indicated by its reading, bearing in mind the fact that the polarity of the line has been reversed by the selector mechanism at the exchange: 34, 51, 52, 92, 86, 90, 106, through the collect coil 99 in reverse direction, 115, 113, 112, 114, through the return 125 130

coil 100 in reverse direction, 110, 102, 85, 101, 50, 49, and 33.

At first thought it might be contended that inasmuch as the collect coil tends to swing the float arm in the direction necessary for collecting the coin, and that, inasmuch as the return coil tends to swing the float arm in the direction necessary for returning the coin, a mere energizing of both of said coils in reverse direction would produce a condition wherein the coils would balance or neutralize each other, and that therefore no desirable result would be produced, but that the float arm would remain stationary in the neutral position. It is possible, however, by properly designing and arranging the coils of the coin box with respect to each other, with respect to their armatures, and with respect to the float arm, to produce a construction wherein this momentary energizing of both of the coils will serve to swing the float arm in the direction necessary for returning the coin, thereby accomplishing the result desired.

The mechanism, whereby the float is locked in its return position after being momentarily swung into such position, will be presently illustrated and described.

An examination of the above arrangement will show that it is impossible for the collect coil to be energized, unless the above mentioned momentary contact is established between the points 112 and 113, or unless the button 98 is pressed to establish connection between the leads 104 and 105. It is also seen that it is impossible for the return coil to be energized unless the momentary contact is established between the points 112 and 113, or unless the momentary contact is established between the points 47 and 48 in the base of the instrument by a removal or replacement of the receiver from or to the hook. Therefore, no change in the electrical condition of the incoming and outgoing lines 27 and 28 can serve to energize either the collect or return coils, while the button 98 remains open or until a coin is passed down the chute to bring the contacts 112 and 113 together, or unless the receiver hook is raised or lowered. These facts are of importance for the reason that, on account of them, the operation of the coin box of the station considered is independent of any other station on the party line, to the extent that an interference with the conditions of the party line by another party on such party line will not collect or return a coin which may be standing on the float arm of the coin box at the station illustrated in Fig. 1. Thus I have removed one of the great objections which has heretofore existed to the use of a coin box in connection with party line telephones operating on an automatic system.

In Fig. 13, I have shown diagrammati-

cally the electrical connections of a modified system which nevertheless embodies certain features of my present invention. In this case also the lines 20 and 21 are the wires of a party line extending from an exchange 22. 70 There are shown four stations connected to this party line, namely, 23, 24, 25, and 26, but only the station 26 is illustrated in detail as the stations 23, 24, and 25 are duplicates of the same. The incoming and outgoing lines of the station 26 are the wires 27 and 28. The ringing box of this station is indicated at 29 and is provided with the customary coils 30 and 31 which are connected in series with a resistance 32, should that be desired. The incoming and outgoing wires connect to the terminals 33 and 34 of the ringing box, and the ringing coils of such box are connected to the outgoing terminal 34 and the ringing terminal 35. 80 85

The base of the telephone is shown at 36, and the transmitter and receiver thereof are shown at 37 and 38. This telephone instrument is provided with a vertically movable post 39 which falls and rises with the rising 90 and falling of the receiver hook in the same manner as was described in connection with the arrangement shown in Fig. 1. This rising and falling of the post 39 operates the leaf contact 40 in the manner previously 95 described to make contact with the point 41 or with another leaf contact 42. The signaling contacts 43, 44, 45, and 46 perform functions similar to those of the arrangement previously described for operating the selector mechanism in the exchange.

The incoming post 33 is connected by a lead 116 to an incoming post 117 in the base of the instrument, and the outgoing post 34 is connected by a lead 118 to an 105 outgoing post 119 in the base of the instrument. A lead 120 connects the ringing post 35 with a ringing post 121 in the base of the instrument, which latter in turn connects by a lead 122 with the fixed contact point 110 41 in the base of the instrument. A lead 123 establishes communication between the leaf 40 and the incoming post 117, so that as long as the receiver remains on the hook, the ringing circuit is closed to receive ring- 115 ing currents which may be delivered over the line from the exchange.

The transmitter connects by leads 124 and 125 with transmitter posts 126 and 127 in the base of the instrument, and the receiver 120 connects by leads 128 and 129 with the receiver posts 130 and 131 in the base of the instrument. A lead 132 is permanently connected between the posts 127 and 130, so that the transmitter and receiver are always in communication with each other. A lead 133 places the leaf contact 42 permanently in connection with the post 131. A lead 134 establishes a permanent connection between the post 126 and the contacts 13 130

and 45 of the signaling mechanism through the medium of the leads 135, 136, and 137.

A double contact push button 138 is mounted at a suitable point, preferably in the base of the instrument, its leaf 139 being adapted to contact a leaf 140 or a leaf 141. Contact normally exists between the leaves 139 and 140, but upon depressing the button this contact is broken and a new contact is established between the leaves 139 and 141. It may be stated at this point that the object of this push button is to bring the coils of the coin box into operation either for the purpose of collecting or 15 turning the coin. The leaf 139 is permanently connected to the outgoing post 119 through the medium of a lead 142, and the leaf 140 is connected to the contact point 44 of the signaling mechanism through the medium of the leads 143 and 144.

With the arrangement thus far described, it will be seen that, as long as the push button remains in its normal position, being the position illustrated in Fig. 13, and 25 as long as the signal contacts 43 and 44 remain together that the transmitter and receiver will be cut across the line in series by the circuit 33, 116, 117, 123, 40, 42, 133, 131, 129, receiver 38, 128, 130, 132, 127, 125, 30 transmitter 37, 124, 126, 134, 136, 137, 43, 44, 144, 143, 140, 139, 142, 119, 118, and 34.

When it is desired to operate the selector mechanism at the exchange the contacts 45 and 46 of the signaling mechanism are 35 brought together and are held together during an interval while the contacts 43 and 44 are opened and closed the necessary number of times to give the desired number of electrical impulses on the line. Under these 40 circumstances, the signaling circuit will be as follows: 33, 116, 117, 123, 40, 42, 133, 131, 145, through the contacts 46 and 45, 135, 136, 137, contacts 43 and 44, 144, 143, 140, 139, 142, 119, 118, and 34. With the 45 connections as above described, it would be possible to operate the selector mechanism without placing a coin in the coin box. I have, however, in the present case provided a precaution against this possibility, similar to 50 the precaution illustrated and described in connection with the arrangement of Fig. 1, namely, the shunting of the contacts 43 and 44 until a coin is inserted into the coin box and allowed to stand on the projecting end 55 of the float arm or a contact carried thereby.

The float arm is designated by the numeral 146. It is pivoted at its end 147, and its end 148 is free to swing in either direction depending upon whether a coin 60 is to be collected or returned, but said end normally stands in a neutral position where it will sustain the coin. A leaf contact 149 is provided above the float arm proper and a similar leaf contact 150 is provided below 65 it. These leaf contacts are rigidly connected

together by an insulating rod or bar 151, so that they rise and fall together, but are both insulated from the float arm proper, although at times one or the other of them may make contact with the float arm. These 70 leaf contacts swing back and forth with the float arm in its movements, and as long as the float arm stands in the neutral position the coin will rest on the projecting end 152 of the upper contact 149. The leaf contacts normally stand in the position shown in Fig. 13 so that contact is established between the float arm 146 and the lower leaf contact 150, but as long as the coin rests on the upper contact 149, the same will be depressed so as to force the lower leaf 150 away from the float arm and to simultaneously carry the upper contact 149 into engagement with the arm.

The contacting of the lower leaf 150 with 85 the float arm shunts the contacts 43 and 44 of the signaling mechanism in the following manner: the leads 136 and 137 connect by another lead 153 with the post 154 in the base of the instrument, which post in turn 90 connects by a lead 155 with a post 156 on the coin box. This post 156 in turn connects by the lead 157 with the float arm 146. Another lead 158 connects the lower leaf contact 150 with a post 159 of the coin box, 95 which in turn connects by a lead 160 with the outgoing line post 119 in the base of the instrument. While the button 138 stands in its normal position the contact 44 communicates with the outgoing line post 119 100 by the circuit 142, 139, 140, 143, and 144. Therefore, under these circumstances the contacting of the lower leaf 150 against the float arm 146 shunts the contacts 43 and 44 by the circuit 137, 153, 154, 155, 156, 157, 105 146, 150, 158, 159, 160, 119, 142, 139, 140, 143, and 144. Therefore in the present arrangement it is necessary to insert a coin into the coin box for the purpose of breaking the contact between the leaf 150 and the 110 float arm 146 before the signaling mechanism can be effectively operated for the purpose of delivering the impulses to the line necessary for operating the selector mechanism.

It might be assumed that, while the coin 115 still stood on the projecting end 152 of the upper leaf contact 149 that a conversation might be carried on and then the coin be returned after the conversation had been 120 completed and without the necessity of collecting the coin into the receptacle, thereby depriving the company of their fee for the service. In the present case, I have guarded against this contingency in the manner similar to that in the case first considered, namely, by throwing the transmitter out of 125 commission or at least interfering with its operation to such an extent that a conversation cannot be carried on as long as the coin 130

stands on the projecting end 152 of the upper leaf contact 149. In the particular arrangement illustrated, I have accomplished this result by shunting the transmitter to thereby divert enough current away from it to prevent its effective operation. This shunting is accomplished by the contacting of the upper leaf contact 149 against the float arm as long as the coin stands on the projecting end 152. It was previously shown that the float arm itself is connected to the terminal 154 on the base of the instrument through the medium of the lead 154. The terminal 154 in turn connects to one of the transmitter posts, namely, 126 through the medium of the leads 153, 136, and 134. Therefore, the float arm is permanently connected to the transmitter post 126. The upper leaf contact 149 connects to the other transmitter post 127 through the medium of the leads 161, 162, post 163 on the coin box, and lead 164. Therefore, as long as a coin rests on the projecting end of the upper leaf contact to force the same down against the float arm, the transmitter is shunted by the circuit 127, 164, 163, 162, 161, 149, 156, 157, 156, 155, 154, 153, 136, 134, and 126. It will be seen that, under these circumstances, the receiver still remains in circuit, so that the calling party can listen and have knowledge as to whether or not the called party responds to the signal.

In order to carry on a conversation after the called party has responded, it is necessary to clear the float arm so as to break contact between the leaf 149 and float arm 146, to thereby cut the transmitter back into service. This is accomplished by collecting the coin into the coin box. The coin box is provided with two coils 168 and 167 which are permanently connected in series by the lead 168, the outer ends of these coils connecting respectively to the posts 169 and 170 of the coin box through the medium of leads 171, 172. The post 170 connects by a lead 174 with the incoming post 117 in the base of the instrument, while the post 169 connects by a lead 175 with a post 176 in the base of the instrument, which post in turn connects by a lead 177 with the contact 141 of the button 138. Therefore, the depressing of the button 138, after cutting out the talking and listening circuits, cuts in both of the coils in series across the line by the circuit 33, 116, 117, 174, 170, 172, 173, coil 136, 168, coil 167, 171, 169, 175, 176, 177, 141, 139, 142, 119, 118, and 34. The coils of the coin box are so wound that, under these circumstances, the float arm will be deflected to that side necessary for collecting the coin.

The ordinary automatic telephone system is so constructed that, in case the called party fails to respond or in case his line is busy, his selector mechanism is reversed in polarity at the exchange. Therefore, if

under these circumstances, an attempt is made to connect with him, a current of reverse polarity will flow through the line of the calling party. Therefore if, under these circumstances, the button 138 should be depressed, a current of reverse polarity will flow through the circuit just described, thereby energizing the coils of the coin box in reverse direction, and causing the float arm to be thrown in the direction for returning the coin instead of collecting the same. Therefore, the depressing of the button 138 will automatically return the coin if the attempt to secure connection with the called party were unsuccessful.

It will be seen from the above that the arrangement of Fig. 13, thus far described, is similar to that shown in Fig. 1, in that until a coin is inserted into the coin box and rests on the float arm while the same stands in the neutral position, it is impossible to effectively operate the signaling mechanism, and in that when the coin is inserted into the coin box and stands on the float arm it serves to interfere with the operation of the transmitter in such a way as to prevent the carrying on of a conversation until the coin has been collected into the coin box.

I shall now describe the particular mechanical constructions and embodiments which I have illustrated in the drawings, for the purpose of carrying into effect the principles and features of invention heretofore described in connection with the electrical diagrams illustrated in Figs. 1 and 13. I shall first describe the mechanism illustrated for use in connection with the arrangement of Fig. 1, and shall then consider the modified mechanisms for use in connection with the arrangement illustrated in Fig. 13.

Figs. 3 to 8 inclusive illustrate one construction of coin box embodying certain features of the present invention. This coin box is of the general form and arrangement familiar in the art, but is provided with certain necessary modifications and additions which adapt it for use in the present case. The upper portion 178 of the coin chute slants downwardly and rearwardly from an opening 179 to a point 180 where it deflects suddenly and extends in a substantially vertical direction. Its shape is such that, when the coin is inserted through the opening 179, it will run down and rest upon the extending end 82 of the leaf contact 76, provided the float arm 73 stands in the neutral position. If the end of the float arm is deflected forwardly—that is to the left in Fig. 3—the coin will be diverted down through a branch chute 181 and will ultimately find lodgment in a coin receptacle 182. If, on the other hand, the float arm had been deflected rearwardly—that is to the right in Fig. 3—the coin will have passed down through

a branch chute 183 and would have found exit at the point 184, to be caught in a pocket 185 of the usual and well known construction.

- 5 The relay used for controlling the movements of the float arm in the present case is preferably what is known as a "polarized relay"—that is, one which when energized with current in one direction will tend to 70 throw the float arm in a corresponding direction, while if it is energized with current in a reverse direction it will tend to reverse the position of the float arm. The coils 99 and 100 described in connection with Fig. 1 75 are the same coils 99 and 100 as are illustrated in Figs. 4 and 5. They are rigidly mounted in a suitable framework and have the active ends of their magnetic cores at the points 186 and 187 of Fig. 5. An arm 188 80 is pivoted on a line extending between the coils so that it can swing about a vertical axis 189, the movements of the arm being controlled by the energizing of the coils 99 and 100.
- 25 The armature is rigidly connected to the float arm 73, so that normally the energizing of the coil 100 swings the float arm to the rear and normally the energizing of the coil 99 swings the float arm forward. The 85 contact leaves 75, 76, 77, and 78 are carried by the float arm but are respectively insulated from each other and from the float arm in the manner shown at 190 in Figs. 6 and 7.
- 35 As is shown particularly in Fig. 7, when a coin 191 descends down through the coin chute, it will strike and rest upon the extending end 82 of the leaf contact 76. With the arrangement illustrated particularly in 90 Figs. 6 and 7, such contacting of the coin against the leaf contact 76 will ground the same on the frame of the coin box. At first thought this might seem to be undesirable, but it will be seen that whenever the coin is 95 resting on the said leaf contact 76 the latter is in contact with the float arm 73 which in turn is grounded on the frame of the box, and therefore no undesirable result will follow from such grounding by the coin. Of course, under some circumstances it might 100 be desired to keep the float arm 73 and all of the leaf contacts away from any possible ground connection, and this could be done by proper insulation of the float arm at its 105 point of bearing or thereabouts, and by proper insulation of the upper surface of the leaf contact 76.
- It was stated in considering the arrangement shown diagrammatically in Fig. 1, that 110 the raising and lowering of the post 39 in the telephone instrument by the operation of the receiver hook serves to cause a momentary contact between the points 47 and 48 in the base of the instrument. It was 115 also shown that the passage of a coin along

the coin chute creates a momentary engagement of the contacts 112 and 113 in the coin box, either one of which momentary contacts will throw an impulse of current into the coils of the relay so as to momentarily swing 70 the float arm in the direction necessary for returning the coin. In order to insure a proper operation under these circumstances, the float arm should be locked in the return position by such impulse, and therefore 75 I have provided positive mechanism for insuring such a locking engagement. In the particular embodiment illustrated, this locking mechanism comprises the finger 192 carried by a lever arm 193 which is pivoted at 80 the point 194 adjacent the coin chute, and is adapted to engage the forward face 195 of the float arm when the latter is thrown rearward for the purpose of catching and holding the same to insure a proper return of the coin. In order to facilitate this locking operation the under face 196 of the end of the float arm is beveled so that it will more readily ride over the finger 192 to insure a proper locking engagement.

With the above arrangement it will be seen that the float arm will be locked in the return position, although swung into such position by a momentary impulse. Means must, however, be provided for disengaging 95 the float arm when the coin is introduced into the coin chute so as to permit the float arm to stand in neutral position ready to engage such coin if need be. For this purpose, I have provided a finger 197 carried by a link 198 which in turn is vertically movable and has its lower end connected to the lever 193 at the point 199. The raising of the finger 197 will serve, through the medium of the said link, to swing the lever 193, 100 thereby lowering its finger and disengaging the float arm to permit the same to return to neutral position. By properly proportioning the parts, the finger 197 will normally stand in such position with respect to the 105 coin chute that the introduction of a coin through the opening 179 will cause a sufficient lowering of the finger 192 to disengage the float arm.

For the purpose of bringing the contacts 115 112 and 113 together momentarily during the passage of a coin along the chute, I have provided a form of construction illustrated particularly in Figs. 3, 4, and 8. In this case a leaf contact 200 is carried by the 120 frame of the coin box, but is insulated therefrom, and stands at a point adjacent the coin chute. Another leaf contact 201, as best shown in Fig. 4, stands immediately behind the leaf 200 and carries a button 202 125 which projects out slightly into the path of the coin. The passage of the coin along the chute will serve to throw the button to one side, thereby bringing the leaf contacts 200 and 201 together momentarily. Inasmuch 130

as this momentary engagement takes place after the coin has passed the finger 197, it will be evident that the float arm will be locked in the return position provided another party is using the party line, all of which action was previously described in detail.

In Figs. 9 to 12 inclusive, I have shown in detail those portions of the mechanical structure in the telephone instrument itself which are herein adapted for obtaining the necessary electrical contacts for the arrangement shown diagrammatically in Fig. 1. The lowering of the receiver hook 203 serves to raise a post 204 which extends down into the base of the instrument and carries an insulating block 205. The leaf contact 40 normally stands in the raised position shown in Fig. 11 to engage the contact point 41. By the lowering of the insulating block 205 which accompanies a removal of the receiver from the hook, the leaf contact 40 is forced away from the contact point 41 and into engagement with the leaf contact 42. Both of the said leaf contacts are carried by an insulating block 206, as shown in Fig. 9.

The contact 47 carried by the block 205 serves to wipe momentarily against the contact 48 upon either an up or a down movement of the insulating block. This construction will be understood particularly by reference to Fig. 10 in which the block 205 is shown in the raised position which it occupies while the receiver stands on the hook. The contact 48 is carried by an insulating block 207.

The signaling mechanism is shown as mounted in the base of the telephone instrument at 208. It is of the usual and well known construction, and embodies the use of a rotatable cam surface 209, the rotations of which serve to make and break the contacts 43 and 44. It is also provided with a swinging arm 210 which brings together the contacts 45 and 46 during the rotation of the cam 209 to insure operation in accordance with the principles discussed in connection with the diagram of Fig. 1. In Fig. 2 I have shown in detail the contacts 43, 44, 45, and 46 in the position which they occupy with respect to the rotatable cam surface for the purpose of more easily identifying them in connection with the electrical diagrams.

In Figs. 14 and 15, I have shown in detail the modifications necessary in the base of the telephone instrument to adapt the same for use in connection with the arrangement shown in Fig. 13. In this case the button 136 is mounted in the base of the telephone instrument and is directly connected to the middle contact leaf 139 by means of an insulating block 211. The contact leaves 139, 140, and 141 are mounted on the insulating block 212 in the base of the instrument, as is shown particularly in Fig. 14.

In Figs. 16 and 17 I have shown in detail the modified construction of float arm necessary for use in connection with the arrangement illustrated in Fig. 13, and the modifications shown in Figs. 16 and 17 will be readily understood by reference to Figs. 3 to 7 inclusive, and particularly Figs. 6 and 7.

I wish particularly to emphasize the fact that with the arrangements herein shown, and described, I have provided instrumentalities of such interrelationship that it is imperative for the calling party to place a coin in his coin box and cause the same to stand on or be supported by the float arm, while the latter stands in neutral position before it is possible for him to effectively operate his signaling mechanism to actuate the selector mechanism of the exchange in order to secure connection with another party. Also that by means of the arrangement herein shown and described, I have made it imperative for the calling party to collect his coin into his coin box before it is possible for him to carry on a conversation with called party. The above results are obtained without carrying the main talking and listening circuits into the coin box, so that the effectiveness of their operation is entirely independent of the effectiveness of any contacts which may be established in the coin box.

I wish also to call particular attention to the fact that all of the above results are obtained without impairing the effectiveness of the listening circuit at any time so that the calling party can always have information as to whether or not he has been successful in securing connection with the called party, and also to the fact that the above results are obtained without in the least impairing the effectiveness of operation of any station as a receiving station to be called by any other station.

I claim:

1. In a telephone system, the combination of talking and listening instrumentalities, signaling mechanism, a prepay box, a float arm in the prepay box, an interconnection between the float arm and the signaling mechanism for the purpose of shunting the latter until a coin is supported by the float arm, and interconnections between the float arm and the talking instrumentality for the purpose of shunting the latter while a coin stands on the float arm, substantially as described.

2. In a telephone system, the combination of talking and listening instrumentalities, selector mechanism operable by pulsations of current, signaling mechanism for delivering pulsations of current to the selector mechanism, a prepay box, a float arm in the prepay box, a polarized relay for actuating the float arm to throw the same either into a position for returning a coin or into a position for collecting the coin, movable con-

tacts carried by the float arm, interconnections between said contacts and the signaling mechanism for the purpose of rendering the latter ineffective to deliver pulsations of current to the selector mechanism until a coin stands on the float arm, interconnections between the contacts of the float arm and the talking instrumentality, for the purpose of rendering the latter ineffective to deliver talking currents while a coin stands on the float arm, means for energizing the polarized relay to swing the float arm into position for returning the coin, and means for energizing the polarized relay for the purpose of swinging the float arm to collect the coin, substantially as described.

3. In a party line telephone system, the combination of selector mechanism operable by pulsations of current, a station including talking and listening instrumentalities, signaling mechanism for the purpose of delivering pulsations of current to the selector mechanism for actuating the same, means for reversing the polarity of the station when connection is established with another station by the selector mechanism, a prepay box, a float arm in the same, a polarized relay for swinging the float arm into position to return a coin or into position to collect the coin, and a contact for energizing the polarized relay in reverse direction to swing the float arm into position to return the coin in case the polarity of the station is reversed by the selector mechanism, substantially as described.

4. In a party line telephone system, the combination of an exchange, a plurality of stations, a party line connecting one or more stations with the exchange, selector mechanism in the exchange operable by pulsations of current from the aforesaid party line to secure connection thereof with another station, the party line station including talking and listening instrumentalities, signaling mechanism for delivering pulsations of current to the line for the purpose of actuating the selector mechanism in the exchange, a prepay box, a float arm, a polarized relay for swinging the float arm either into position for returning a coin or into position for collecting the coin, the selector mechanism acting to reverse the polarity of the line in case the same is in use, and a contact for delivering an impulse of current of reversed direction to the relay in case the party line

is in use to thereby swing the float arm into position to return the coin, substantially as described.

5. In a party line telephone system, the combination of an exchange, one or more party lines connected to the same, selector mechanism operable by pulsations of current for each party line, each selector mechanism being adapted to reverse the polarity of its party line when the latter is in use, one or more stations connected to each party line, each station including talking and listening instrumentalities, signaling mechanism for actuating the corresponding selector mechanism at the exchange, a prepay box, a float arm, a polarized relay for swinging the float arm either into position for returning the coin or into position for collecting the coin, and a contact for delivering an impulse of current to the polarized relay for the purpose of swinging the float arm into position to return the coin in case the line is in use and had its polarity reversed by the selector mechanism at the exchange, substantially as described.

6. In a telephone system, the combination of talking and listening instrumentalities, connections for placing the same in series across a party line, selector mechanism operable by pulsations of current, signaling mechanism for delivering pulsations of current to the selector mechanism for actuating the same, a prepay box, a float arm in the same adapted, while in the neutral position, to sustain a coin, and adapted to return the coin when thrown in one direction, and to collect the coin when thrown in the other direction, movable contacts carried by said float arm, a resistance coil, interconnections between the signaling mechanism and the float arm for rendering the signaling mechanism ineffective to deliver pulsations of current to the selector mechanism until a coin is supported by the float arm, and interconnections between the float arm, resistance coil, and talking instrumentality for the purpose of shunting the latter with said resistance coil as long as a coin is supported by the float arm, to thereby render the talking instrumentality ineffective to deliver talking currents to the line, substantially as described.
